Primary Examiner — Mary Ann Calabrese*Assistant Examiner* — Sloan Rozin(74) Attorney, Agent, or Firm — Husch Blackwell LLP(57) CLAIM

We claim the ornamental design for a neck label for a bottle, as shown and described.

DESCRIPTION

FIG. 1 is a front perspective view of a neck label showing the new design;

FIG. 2 is a front elevation view thereof;

FIG. 3 is a rear elevation view thereof;

FIG. 4 is a left side elevation view thereof;

FIG. 5 is a right elevation view thereof;

FIG. 6 is a top plan view thereof; and,

FIG. 7 is a bottom plan view thereof.

The broken lines and the area within the broken line in the Figs. depict environmental subject matter that forms no part of the claimed design.
